UNITED STATES PATENT OFFICE.

EMMET K. MOORE, OF NEW YORK, N. Y., ASSIGNOR TO NATIONAL CARBON COMPANY, INC., OF NEW YORK, N. Y., A CORPORATION OF NEW YORK.

DESIGN FOR A SALES-CASE.

56,452.

Specification for Design.

Patented Oct. 26, 1920.

Application filed October 22, 1919. Serial No. 332,569. Term of patent 3½ years.

To all whom it may concern:

Be it known that I, EMMET K. MOORE, a citizen of the United States, residing at No. 330 West 87th street, in the city, county, and State of New York, have invented a new, original, and ornamental Design for a Sales-Case, of which the following is a specification, reference being had to the accompanying drawing, forming a part thereof.

The figure is a perspective view of the sales case, showing my new design.

I claim:

The ornamental design of a sales case, as shown.

EMMET K. MOORE.
